UNITED STATES PATENT OFFICE

153,209

DESIGN FOR A MOLDED PULP
CUSHION PAD

William J. De Reamer, Crown Point, Ind., assignor to Mapes Consolidated Manufacturing Company, Griffith, Ind., a corporation of Delaware

Application May 6, 1947, Serial No. 138,842

Term of patent 14 years

(Cl. D58—16)

To all whom it may concern:

Be it known that I, William J. De Reamer, a citizen of the United States, and a resident of Crown Point, county of Lake, and State of Indiana, have invented a new, original, and ornamental Design for a Molded Pulp Cushion Pad, of which the following is a specification, reference being had to the accompanying drawing, forming a part thereof, in which Fig. 1 is a top view of a quarter corner section of a molded pulp cushion pad, showing my new design. Fig. 2 is a bottom view of the quarter corner section of the pad appearing in Fig. 1; Figs. 3, 4 and 5 are vertical detail sectional views through parts of the pad, as taken on the lines 3—3, 4—4 and 5—5 respectively and on a scale enlarged over that of Fig. 1.

The other three sections of the pad are identi-

cal in appearance with the quarter section shown and are arranged in proper relation to complete the pad.

I claim:

The ornamental design for a molded pulp cushion pad, substantially as shown and described.

WILLIAM J. DE REAMER.
